PALLET MAGAZINE

John Miller, Cambria Heights, N.Y., assignor to The F. & M. Schaefer Brewing Company, Brooklyn, N.Y.
Filed June 16, 1961, Ser. No. 117,722
5 3 Claims. (Cl. 221—290)

The present invention relates to an improved magazine for pallets particularly pallets which are bulky and have considerable weight such as are used in the palletizing of kegs and the like.

An object of the invention is to provide a construction for feeding the bottom pallet to a conveyor for movement to a main palletizing station or an intermediate pallet station.

A further object of the invention is to provide a construction wherein a controlled lift supports the pile of pallets in the magazine during certain periods and to provide retaining means at other periods controlled by the movement of the lift.

A still further object is to provide retaining means for the pallets stacked in the magazine which are operative to release at predetermined periods the bottom pallet of the stack.

With the above and other objects in view, a preferred form of the invention is shown in the drawings in which:

FIGURE 1 is a plan view showing the arrangement for feeding base pallets to the main palletizing station and intermediate pallets to an intermediate transfer station.

FIGURE 2 is diagrammatic view illustrating the controls for removing the bottom pallet from a stack of pallets.

FIGURE 3 is a side view of the magazine with parts broken away.

FIGURE 4 is a cross-sectional view taken upon section line 4—4 of FIGURE 3.

FIGURE 5 is a view similar to FIGURE 4 showing the parts in a different position, and

FIGURE 6 is also a similar view to FIGURE 4 showing the parts in still another position.

In FIGURE 1 a magazine 30 is shown for the base pallets 31 which are conveyed to the main palletizing station 32. The kegs or other bulky articles which are to be palletized are fed by the skids 33' to the station 32. The palletized load is then removed from the station 32 via the conveyor 33. When a plurality of tiers are built at the main palletizing station 32 then intermediate pallets are fed from the intermediate pallet magazine 34 via the conveyor 25 to the intermediate transfer station 35. The intermediate pallets are shown at 36.

The invention applies to both magazines 30 and 34 but will be particularly described with reference to magazine 34 for intermediate pallets. The construction is used particularly in a palletizing apparatus such as disclosed in Serial No. 498,646 filed April 1, 1955 by John Miller and Vincent J. Russman, entitled "Conveyor Keg Palletizing Device" now Patent No. 3,022,617. The magazine 34 comprises a frame 37 extending from the floor 38 generally to the ceiling 39. Associated with such frame enclosing the pallets are the gates 40 which are opened by the pistons 43 and 44 by appropriate mechanisms such as shown in the above application whenever it is desired to load the magazine. The pallets will then be stacked in the magazine as shown in FIGURES 4 to 6. Located directly below the center of the pallets is a lift 11 having a platform 12 thereon. The lift 11 is reciprocated in the cylinder 42 shown diagrammatically in FIGURE 2. The lift operates between the conveyor chains 25 which rotate over the sprockets 45 which may be driven in any desired way. At the start of an operation for dispensing a pallet from the magazine the stack of pallets 36 are retained as shown in FIGURE 4 by the fingers

2

20 and 21. The fingers 20 and 21 are pivotally connected to links 46 which are pivoted to the frame at 47 and are moved inwardly to the position shown in FIGURES 4 and 6 or outwardly as shown in FIGURE 5 by the rods 48. The rods 48 are connected by appropriate rods and gears as shown diagrammatically in FIGURE 1 in dotted lines to the piston rod 49 reciprocating in a cylinder 13. The detailed construction of the retaining fingers 20 and 21 is shown in the application above referred to.

When a bottom pallet 36 is lowered by the piston 11 until it rests upon the conveyor chains 25 it is carried by such chains until it strikes a stop piston 28 and is released by such stop piston 28 at the appropriate time to be forwarded to either the palletizing station or the intermediate pallet transfer station. Upon being carried forward to the intermediate pallet transfer station the pallet 36 will strike a switch 27 which then initiates the upward movement of the piston 11 by operating the valve 19. A similar procedure for initiating the action of a similar lift 11 at the base pallet magazine is initiated by the switch 50 upon removal of a palletized load from the palletizing station by the conveyor 33. The stop piston for the base pallets is indicated at 51.

Upon upward movement of the piston 11, see FIGURE 2, the platform 12 thereon which is connected to the chain 14 initiates a movement of such chain around the sprockets 52 clockwise. At the proper place in such chain 14 there is positioned a cam 15. The cam 15 will 30 operate in proper sequence the valves 16, 17 and 22. As above indicated the valve 19 has been opened by the switch 27 so that hydraulic fluid is pumped into the cylinder 42 to raise the piston 11. Then as the chain 14 moves clockwise the cam 15 trips the first valve 16 and this valve will control the further movement of the piston 11 and the valve 19 is out of action. The piston 11 continues its upward movement and the cam 15 trips the valve 17. The valve 17 operates the piston 49 reciprocating in the cylinder 13 to operate the fingers 20 and 21 40 which are now withdrawn to the position shown in FIGURE 5.

Prior to complete withdrawal of the fingers 20 and 21, the piston 11 continues its upward movement until the cam 15 strikes the valve 22. At such time the piston 11 is in its upward position as shown in FIGURE 5 supporting the stack of pallets and the fingers 20 and 21 are completely withdrawn from such stack. The operation of valve 22 reverses the hydraulic feed to the cylinder 42 and the piston 11 begins its downward movement 50 carrying the load of pallets 36. The piston 11 moves downwardly the depth of one pallet and stops. This is all valve controlled. At the momentary halting of the platform 12 the fingers 21 and 20 move back into the position shown in FIGURE 6 and again support the entire stack of pallets with the exception of the lowermost which rests upon the platform 12. The piston 11 again starts its movement downwardly until it deposits such lowermost pallet upon the conveyor chain 25 and the pallet is moved away from the chains 25.

60 As previously pointed out such pallet dispensed from the magazine moves forward only to where it is stopped by the stop piston 28 and is moved forwardly again by the conveyors 25 where it trips the switch 27 which again initiates the cylindrical movement set forth above. The stop piston 28 is released when a pallet 36 or 31 is removed from either the intermediate pallet transfer station or the palletizing station by an appropriate switch.

On the downward movement of the lift 11 the chain 14 will move counterclockwise and the cam 15 upon tripping the valves 17 and 16 will reverse the feed to the cylinders 13 and 42.

It is thought that the invention and its advantages will

be understood from the foregoing description and it is apparent that various changes may be made in the form, construction and arrangement of the parts without departing from the spirit and scope of the invention or sacrificing its material advantages, the form hereinbefore described and illustrated in the drawings being merely a preferred embodiment thereof.

I claim:

1. A magazine for pallets and the like and dispensing means therefor comprising a container wherein said pallets may be stacked, means supporting said stacked pallets, a lift movable vertically upwardly and downwardly under said stacked pallets, means for removing said supporting means when said lift is in its upper position and then returning said supporting means when said lift has moved downwardly the depth of one pallet, a conveyor for moving pallets from said container extending below said container at the sides of said lift, an endless chain driven by said lift, a cam upon said chain and means cooperating with said cam controlling the movements of said supporting means and said lift.

2. A magazine for pallets and the like and dispensing means therefor comprising a container wherein said pallets may be stacked, means supporting said stacked pallets, a lift movable vertically upwardly and downwardly under said stacked pallets, means for removing said supporting means when said lift is in its upper position and then returning said supporting means when said lift has moved downwardly the depth of one pallet, an endless chain

5 driven by said lift, a cam upon said chain and a series of fixed spaced valves cooperating with said cam controlling the movements of said supporting means and said lift.

3. A magazine for pallets and the like and dispensing means therefor comprising a container wherein said pallets may be stacked, means supporting said stacked pallets, a lift movable vertically upwardly and downwardly under said stacked pallets, means for removing said supporting means when said lift is in its upper position and then returning said supporting means when said lift has moved downwardly the depth of one pallet, an endless chain driven by said lift, a cam upon said chain and three fixed valves in spaced relation cooperating with said cam controlling the movements of said supporting means and said lift.
